UNITED STATES PATENT OFFICE.

FLOYD A. WIEGMAN, OF SIOUX CITY, IOWA.

POCKET CHECK-PROTECTOR.

1,373,545.

Specification of Letters Patent.

Patented Apr. 5, 1921.

Application filed October 18, 1919. Serial No. 330,380.

To all whom it may concern:

Be it known that I, FLOYD A. WIEGMAN, a citizen of the United States, and a resident of Sioux City, in the county of Woodbury and State of Iowa, have invented certain new and useful Improvements in Pocket Check-Protectors; and I do hereby declare that the following is a full, clear, and exact description thereof, reference being had to the accompanying drawings, and to the letters of reference marked thereon, which form a part of this specification.

This invention relates to improvements in pocket check protectors, and consists of the matters hereinafter described and more particularly pointed out in the appended claims.

The object of the invention is to provide a small compact device, adapted to be carried in a coat or like pocket, which may be operated to inscribe in an unalterable manner, the amount payable on a bank check or like commercial paper. The advantages of the invention will more fully appear as I proceed with my specification.

In the drawings:

Figure 1 illustrates a top plan view of a pocket check protector, embodying my invention, and shows the bank check being operated upon, in position therein.

Fig. 2 illustrates on an enlarged scale, a transverse vertical section through the check protector.

Fig. 3 illustrates a view similar to that shown in Fig. 2, but with the parts in changed relation.

Fig. 4 illustrates a horizontal, sectional view through the check protector, the plane of the section being indicated by the line 4—4 of Fig. 2.

Fig. 5 illustrates a horizontal, sectional view through a post forming a part of the check protector, the plane of the section being indicated by the line 5—5 of Fig. 2.

Fig. 6 illustrates a face view of one of the impression members embodied in the improved check protector.

Referring now in detail to that embodiment of the invention illustrated in the accompanying drawings, 10 indicates the circular base of the check protector, which has an upright annular flange 11, and a bottom wall 12, which is dished at its middle as shown in Figs. 2 and 3. Fixed to the top surface of said bottom wall, at its center is a disk 13 which includes an upright, inte-

riorly threaded tube 14. Arising from said disk are three arcuately spaced studs 15, each having a reduced top end part 15^a, and diametrically opposite one of said studs is a fourth stud 16, the purpose of which will appear later. Fixed to the flat, horizontal part of the wall 12 is a flat plate 17, which includes a plurality of arcuately spaced radial arms 18, to the outer ends of which are secured impression platens 19, in the form of segmental blocks having a serrated top surface. The serrations are preferably arranged at a 45° angle to the median line of the associated arm 18. As shown the outer ends of each platen abut against the flange 11 of the base plate 10.

Secured to the top surface of said plate 17 is a second and similar plate 20, having resilient, arcuately spaced radial arms 21, which are extended into the space between said arms 18 of the plate 17. To the outer end of each arm 21, is secured an inking device 22, in the form of a segmental felt pad, the said pads being arranged in alternation with respect to the platens 19. Preferably the operative surfaces of the ink pads are arranged in a plane below the operative surface of the impression platens.

23 indicates a post which is so mounted on the tube 14 as to be capable of both a limited endwise and rotative movement thereon. In the bottom of said post are three arcuately spaced recesses 24, and three smaller associated recesses 24^a, on the same circle as the recesses 24. Each small recess 24^a, is spaced from its associated recess 24, a distance equal to the angular distance between the arms 18 of the plate 17. Spaced opposite one of the recesses 24, in the periphery of the post, is an arcuate recess 25 in which is engaged the stud 16 before referred to, the studs 15 normally engaging in the recesses 24. In the top end of said post is an enlarged recess 26, in which slides the head 27 of a screw 28, which is threaded into the top end of the tube 14. Expansion coiled springs 29, seated in recesses 30 in said post and which open into the recess 26, engage the under side of the screw head 27, and act to urge the post toward and into seating engagement on the disk 13. The ends of the springs 29, engaging the screw head, carry balls 31 to eliminate friction. Said post extends through 110 and has guided bearings on its periphery in center holes 32, in the plates 17 and 20.

Secured to the top end of the post is a top plate 33 and a knob 34, screws 35, which are threaded into the top end of said post, passing through said plate and knob, said knob 5 having a knurled periphery to permit of its being easily grasped. The top plate 33 has a plurality of arcuately spaced, radial, resilient arms 36, the upwardly bent, outer ends of which terminate in depending flanges 37. To the bottom surface of the outer end of each arm is secured a character impression member or block 38. As shown in this particular instance, said plate includes fourteen of such arms, the character 10 blocks being numbered from 1 to 0 and also including other desirable characters such as \$, =, and the like. On the top surface of each arm as indicated at 39, is a character corresponding to the character on the block 15 38 on the other side of said arm and beneath said character is a line 40 arranged at right angle to the median plane of the associated arm. This line acts as a guide and when brought into alinement with "Amount payable" line of the check to be protected, insures the accurate inscription of the desired 20 character on said "Amount payable" line of the check.

Normally the operative surfaces of said 25 impression blocks 38, which are serrated as shown in Fig. 6, engage upon the ink pads, this being the position when the device is being carried in the pocket.

To use the check protector, the base 10, 30 is held in one hand of the operator, with the other hand grasping the knob 34. The knob is then moved upwardly, away from the base a distance greater than the length of the studs 15, after which a rotative movement 35 is imparted to said knob, until said rotative movement is stopped by engagement of the stud 16, with the other end of its associated slot or recess 25, in the bottom end of the post 23. This will bring the studs 15, 40 into alinement with the recesses 24^a in the bottom end of the post 23, and into which the top reduced ends 15 of said studs will now enter. This will lock the top plate in a position wherein all of the character 45 impression bearing arms 36 are arranged in the radical planes of the impression platens 19, but spaced a distance above the same as shown in Fig. 3. With the parts in this position, a bank check, which may or may 50 not be already filled out, is inserted between the impression platens 19, and the impression members 38, the guide line 40 on the desired arm 36 being brought into alinement with the "Amount payable" line on the 55 check. The said desired arm is now pressed downwardly toward the base. This may be done either while the device is held in the hands of the operator, or after the base has been placed upon the table or like support. 60 This pressure upon said arm will cause the 65

check to be moved into engagement with the impression platen, to thereafter receive on its top surface the impression of that particular block or member 38 being used, the impressions being as shown on the check in Fig. 1. Said impressions are pressed into the paper, and the ink on the said impression member will color said impressions so that the inscriptions on the check will be unalterable and erasure proof. Such other 70 characters as may be desired may be impressed or inscribed on the "Amount payable" line by turning or rotating the device as a whole to bring the desired character into proper position for the next impression, 75 the prior impression appearing in the space to the left of the next arm 36 to be used, thus providing a spacing guide for the characters to be impressed or inscribed upon the check. To return the parts to their normal 80 positions, the knob 34 is again grasped and pulled outwardly to release the stud extensions 15^a from the recesses 24^a, after which the knob is rotated in the reverse direction, which direction is limited by the stop 16 as 85 before described. This will bring the studs 15 into registry with the holes 24 in the post, and the springs 29 will again urge said top plate toward the base plate. When the parts are in this position, the impression 90 members again engage upon the inking pads 22.

My device possesses many advantages, as it is compact and light in weight and may be readily carried about in the coat pocket, 100 and is ready for use at all times. With the operative surface of the impression platen arranged in the plane above the ink pads, there is no possibility of producing a smear on the back of the check, by reason of the 105 engagement of said check with the ink pads.

Should it be desired, those pads associated with the characters shown on the bottom of the check protector in Fig. 1, may be of a different color than those associated with the numerals 1 to 0, and thus a contrast may be produced between the impressions or inscriptions made upon the check.

While in describing my invention, I have referred to certain details of mechanical construction and arrangement of parts, I do not wish to be limited thereto, except as may be pointed out in the appended claims.

I claim as my invention:

1. A pocket check protector comprising a 120 circular base plate, impression platens, arcuately spaced on said base plate, segmental inking devices on said base plate between said platens, an impression plate rotatively mounted with respect to the base plate, said 125 impression plate including a plurality of radial resilient arms, each carrying an impression member adapted to engage with an associated impression platen or an associated inking device, and means for limiting 130

the rotative movement of the impression plate on said base plate so that said impression member will register either with the platens or with the inking devices.

2. A pocket check protector comprising a circular base plate, a plurality of impression platens arcuately spaced on said base plate, an ink pad between adjacent impression platens, the operative surface of the ink pads being in a plane below the operative surface of the impression platens, an impression plate, said impression plate including a plurality of radial, resilient arms, each carrying an impression member, normally engaging an associated ink pad, and means connecting said impression plate with the base plate, said means permitting of a movement of said impression member to clear said ink pads and also a rotative movement of said impression plate to bring said impression members into registry with the impression platens.

3. A pocket check protector comprising a circular base plate, a plurality of impression platens, arcuately spaced on said base plate, an ink pad between adjacent impression platens, the operative surface of the ink pads being in a plane below the operative surface of the impression platens, an impression plate, said impression plate including a plurality of radial, resilient arms each carrying an impression member, normally engaging an associated ink pad, and means connecting said impression plate with the base plate, said means permitting of a movement of said impression plate away from the base plate to allow said impression member to clear said ink pads, and also a limited rotative movement of said impression plate to bring said impression members into registry with the impression platens.

4. A pocket check protector comprising a circular base plate, a plurality of impression platens, arcuately spaced on said base plate, an ink pad between adjacent impression platens, the operative surface of the ink pad being in a plane below the operative surface of the impression platens, an impression plate, said impression plate including a plurality of radial, resilient arms each carrying an impression member, normally engaging an associated ink pad, means connecting said impression plate with the base plate, said means permitting of a movement of said impression plate away from the base plate to allow said impression member to clear said ink pads, and also a limited rotative movement of said impression plate to bring said impression members into registry with the impression platens, and a member fixed with respect to said impression plate and by means of which both the said movement away from said base plate and said rotative movement may be imparted to said impression plate.

5. A pocket check protector comprising a circular base plate, a plurality of segmental impression platens arcuately spaced on said base plate, an ink pad between adjacent impression platens, the operative surface of the ink pads being in a plane below the operative surface of the impression platens, a post mounted at one end on said base plate, and a plate fixed to the other end of said post, said plate including a plurality of radial, resilient arms, each carrying an impression character, normally engaging an associated ink pad, said post being capable of movement away and toward said base plate and also a limited rotative movement with respect to said base plate, to permit said impression characters to clear said ink pads and to be brought into registry with the impression platens.

6. A pocket check protector comprising a circular base plate, a plurality of segmental impression platens arcuately spaced on said base plate, an ink pad between adjacent impression platens, the operative surface of the ink pads being in a plane below the operative surface of the impression platens, a post mounted at one end on said base plate, and a plate fixed to the other end of said post, said plate including a plurality of radial, resilient arms, each carrying an impression character, normally engaging an associated ink pad, said base and post having co-acting pins and recesses permitting of a limited movement of said post away and toward said base plate and also a limited rotative movement of said post with respect to the base plate, to permit said impression characters to clear said ink pads and to be brought into registry with the impression platens.

7. A pocket check protector comprising a circular base plate, a plurality of segmental impression platens arcuately spaced on said base plate, an ink pad between adjacent impression platens, the operative surface of the ink pads being in a plane below the operative surface of the impression platens, a post mounted at one end on said base plate, a plate fixed to the other end of said post, said plate including a plurality of radial, resilient arms, each carrying an impression character, normally engaging an associated ink pad, said post being capable of movement away and toward the base plate and also a limited rotative movement with respect to said base plate, to permit said impression members to clear the ink pads, and to be brought into registry with the impression platens, and means within the post urging said impression plate toward the base plate.

8. A pocket check protector comprising a circular base plate, a plurality of segmental impression platens, arcuately spaced about the base plate, an ink pad between adjacent impression platens, resilient means for sup-

porting the ink pads with their operative surfaces below the plane of the platens, a plate, said plate including a plurality of radial arms, each carrying an impression character normally engaging an associated ink pad, and means connecting said impression plate with the base plate, said means permitting of a movement of said impression plate away from the base plate to allow the 10 impression characters to clear the ink pads and also a rotative movement of said impression plate to bring said impression characters into registry with the impression platens.

9. A pocket check protector comprising a 15 circular base plate, a plurality of segmental impression platens, arcuately spaced about the base plate, a second plate, fixed with respect to the base plate and having a plurality of resilient, radial arms extending into the 20 spaces between said platens, ink pads carried

by said arms, a top plate including a plurality of radial arms, each carrying an impression character normally engaging an associated ink pad, and means connecting said top plate with the base plate, said means 25 permitting of a movement of said top plate away from the base plate to allow the impression characters to clear the ink pads and also a rotative movement of said top plate to bring said impression characters into registry with the impression platens. 30

In testimony that I claim the foregoing as my invention, I affix my signature in the presence of two witnesses, this 10th day of October, A. D. 1919.
